SASH LOCK

Axel W. Ahlgren, Rockford, Ill., assignor to
Amerock Corporation, Rockford Ill., a corporation of Connecticut

Filed Aug. 27, 1968, Ser. No. 13,291

Term of patent 14 years

Int. Cl. D8—03

U.S. Cl. D8—111

FIG. 1 is a plan view of a sash lock incorporating my new design.

FIG. 2 is a side view of the sash lock as seen from the right of FIG. 1.

FIG. 3 is a plan view of the sash lock with the parts in a different position.

FIG. 4 is a side view as seen from the right of FIG. 3.

FIG. 5 is an elevational view of the sash lock as seen from the bottom of FIG. 1.

FIG. 6 is a perspective view of one of the parts of the sash lock.

FIG. 7 is a perspective view of the other part of the sash lock.

I claim:

The ornamental design for a sash lock, as shown and described.
